UNITED STATES PATENT OFFICE.

JAMES A. BROGAN, OF LAWRENCE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WELTING.

1,278,844.

Specification of Letters Patent. Patented Sept. 17, 1918.

Application filed August 26, 1915. Serial No. 47,512.

To all whom it may concern:

Be it known that I, JAMES A. BROGAN, a citizen of the United States, residing at Lawrence, in the county of Essex and State of Massachusetts, have invented certain new and useful Improvements in Welting; and I do hereby declare the following to be a full, clear, and exact description of the invention, such as will enable others skilled in the art to which it appertains to make and use the same.

The present invention relates to an improved welting for use in the manufacture of welt shoes.

15 Welting used in the manufacture of Good-year welt shoes is generally prepared by cutting with a grooving knife a half-round strip of leather from the flesh side of a plain strip of welting leather to form the groove, 20 and by skiving off the inner edge of the strip with a skiving knife to form the bevel. The bevel is shaped to fit closely in the angle formed at the junction of the shoe upper with the insole, and the groove receives the 25 seam and allows the welting to be readily bent into shape to conform to the angle of the upper and outsole. The material removed at the bevel and groove of the welt weakens it, because the fiber of the inner layers of leather is softer and coarser grained than the outer layers or grain fiber of the leather. The inseam for uniting the welting to the shoe upper and insole passes through the bevel and lies in the groove, and 30 it often happens that during the formation of the inseam, the stitches will be pulled entirely through welting having a cut groove and bevel. Moreover, it often happens that in sewing the welting to the lasted shoe, the inseam will be sewed so near to the inner 35 edge of the welting that the skived surface is partially visible in the crease between the upper and the welting. Where blackened welting is used, the appearance of the 40 lighter colored skived leather is particularly noticeable and necessitates a special treatment of the crease when the shoe is finished. Further, when the seam is far enough back from the inner edge so that the 45 skived bevel is not noticeable, a considerable 50

portion of the welting will be wasted during the inseam trimming operation.

The objects of the present invention are to provide an improved welting which is well suited for the manufacture of welt 55 shoes and which will overcome the above-mentioned disadvantages.

In accordance with these objects, one feature of the invention contemplates the provision of a welting having an inseam receiving edge of a portion offset from the body of the welting to form a rib that will conform closely and accurately to the shape of the shoe upper at its junction with the insole. In the preferred form of the invention, the inseam receiving edge of the 60 welting consists of a groove on the under face of the welting, a bevel on the upper face of the welting, and a rib which forms a continuation of the bevel, the material 65 between the groove, and the bevel and rib being compressed to form a rigid, strong, seam-receiving area. To insure an economical use of welting, no material is removed from the grain side or upper face of the 70 welting, and both the rib and the bevel are 75 covered with the grain fiber of the leather.

In addition to the features above referred to, the present invention also consists in a 80 welting having certain novel features hereinafter described and claimed, the advantages of which will be obvious to those skilled in the art from the following description.

In the drawings Figure 1 is a perspective 85 view of a welting embodying the preferred form of the invention, showing the upper face and offset rib, and Fig. 2 is a perspective view of the welting showing the under face and the groove.

In the illustrated embodiment of the invention, the welting consists of a strip of leather welting material having a seam-receiving edge 10 and a body 12. This welting is made from a strip of leather having a 95 substantially rectangular cross-section. The strip is usually tempered before treatment and fed into a welt preparing machine. Upon entering the machine, a V-shaped strip of leather is removed by a grooving knife 100.

along the inner edge of the welting on the flesh side 14 to mark the location of the groove 16. After leaving the grooving knife, the welting is advanced between upper and lower molding rolls, which form the seam-receiving edge. The upper and lower molding rolls have a special contour which progressively shapes and enlarges the groove 16, a rib 18, and a bevel 20 as the 5 welting is advanced through the machine. The upper molding rolls are arranged to feed the welting by means of a series of feeding teeth which place a series of indentations 22 upon the flesh side of the body of the welting and tend to roughen it. The lower molding rolls contact the grain side or upper face 24 of the welting. These rolls may move faster than the welting, which tends to glaze the surface of the welting and aids in compressing and shaping the seam-receiving edge to form the rib and bevel. As the completed welting emerges from the preparing machine, the seam-receiving edge 10 is offset from the body of the welting and the rib on the upper face is at the junction of the edge with the body of the welting. Also the seam receiving edge projects below the under face of the welt, which facilitates guiding the needle of the inseam sewing machine into the groove. The material 15 between the groove 16 and the rib 18 and bevel 20 is strongly compressed and permanently molded into shape. The compression tends to strengthen the edge and since the grain fiber of the welting has no portion removed, a very strong seam receiving edge is formed. The angle and shape of the 25 rib may be varied and the distance of the rib and a rib on its upper face opposite the groove from the edge may be varied by employing different types of molding rolls. The rib 18 may be accurately shaped to fit in the angle formed by the upper at its junction with the insole. Further, by enlarging the rib, a shoe can be given an appearance which will closely imitate a cork sole. The bevel formed by the rolls is rounded to accurately fit against the upper at its junction with the insole. The rounded bevel will make a 30 tighter joint with the upper than the usual form of welting which has an angular bevel formed by cutting a flat face.

By compressing the seam-receiving edge, the groove may be placed very near the inner edge of the welting and still retain sufficient strength for uniting the welting to the upper. Also, since none of the grain fiber of the welting has been removed, the seam for uniting the welting with the upper can be placed close to the inner edge of the welting without marring the appearance of the welting. This is important in the manufacture of welting, because by holding the groove close to the inner edge of the welting, the seam can be placed therein and compar-

atively little welting will be removed on the inseam trimming operation. Through this means, also, a narrower width of welting can be used than was heretofore possible when a portion of the grain fiber of the leather was removed.

After the welting has been united to the upper and insole, the outsole is cemented to the bottom of the insole and the under face of the welting. In the usual treatment of 75 welting in which the bevel and groove are formed by cutting away a portion of the welting, the under face or flesh side of the welting is glazed by the feeding rolls and does not form an efficient surface to which 80 to cement the outsole. The indentations 22 placed on the flesh side of the welting roughen it and form a series of pockets for holding the cement, so that the under surface of the improved welting is well suited 85 for cementing to the outsole.

In describing the welting, the term "upper face" is intended to refer to the face of the welting which lies uppermost and is visible in the completed shoe; the term "under face" is applied to the face of the 90 welting which lies against the outsole, and the term "inner edge" of the welting is the 95 edge which is sewed to the upper and insole in the completed shoe.

Having thus described the preferred form 95 of the invention, what is claimed as new

is:

1. As an article of manufacture, a strip of welting for use in the manufacture of 100 shoes comprising, a strip of welting material removed, a very strong seam receiving edge, a rib on its upper face opposite the groove, and having its edge outside of the 105 body of the welt to form a rib offset from the body of the welt to form a bevel.

2. As an article of manufacture, a strip of 110 welting for use in the manufacture of shoes comprising, a strip of welting material provided with a groove and a bevel, the face of the groove being glazed and the under face of the strip being roughened.

3. As an article of manufacture, a strip of 115 welting for use in the manufacture of shoes comprising, a strip of leather welting material having a groove and a bevel, and a rib opposite the groove, said bevel and rib being pressed into form and covered with the grain fiber of the leather.

4. As an article of manufacture, a strip 120 of welting for use in the manufacture of shoes comprising, a strip of welting material having its inner edge compressed to form a rigid area for a seam, and said inner edge offset to form a rib to lie in close to the upper when the welting is attached to a shoe.

5. As an article of manufacture, a strip of 130 welting for use in the manufacture of shoes comprising, a strip of welting material hav-

ing a seam-receiving edge, a rib on its upper face, and its under face roughened to form a cementing surface.

6. As an article of manufacture, a strip of welting for use in the manufacture of shoes comprising, a strip of leather welting material having its inner edge offset and

beveled to form a seam-receiving area, and a rib on its upper face at the junction of the offset portion with the body of the welt, 19 said bevel and rib being covered with the grain fiber of the leather.

JAMES A. BROGAN.
